Phila. Blake & Eli Whitney Blake, Eli's Attn. C. A. N.

S. M. S. Patent

The Schedule referred to in the S. M. S. Patent and striking part of the same containing a description of the works of the said Phila. Blake & Eli Whit. Blake, both of New-Haven in the County of New-Haven in the State of Connecticut, inventors of said New-Haven Locks have invented and constructed several new and useful improvements in, and to the use of the locks consisting in certain modifications of the structure of Locks as heretofore made whereby the manufacture is facilitated and the expense diminished & whereby the Mortise Lock may be reduced to such a compass, that it may be put into a Mortise into doors, the same to receive the Mortise Locks heretofore in use. The following is a full and accurate description of the Lock as described by the inventor of the improvements, to wit:

The Case or part which contains or receives the parts of the Lock, a single piece of sheet iron or other metal whose length is equal to the distance that the lock is to reach in from the edge of the door and whose width is equal to the width of the two sides and one edge of the case being four lines of right angles forms the two sides ~~or bottom~~ of the case, the end of that piece being formed as desired by bolting, riveting, brazing, or otherwise, to the edge of a plate or plate through which the bolt passes when driven into the case, it containing the key hole or that part which receives the end of the key as made for the sides close to the bottom of the case & not to cut across the bottom of the case, one edge shall be cut to allow of the passage of the bit of the key which is to enter the key is introduced upon a velocity below the bottom of the case to turn the key to revolve on its axis and to bring the bit to turn the case & enter the striking part of the lock the bottom of the case is to be further cut away the cutting may be in a form corresponding to the width or import to the passing the key head constituting heads to the lock.

The Bolt. This has a square head & thin shank as in common locks. The form and position of the shank may be varied to make it vary in the locks to suit the shank that may be chosen to give a firm and instant hold of

so long a slot in the edge of the blank for the key to pass into, to allow the bolt
sliding vertically, may be cut in the side of the key corresponding to the slot in
order to the correct position of the blank so that the extremity of the bit may
pass by the lower edge of the blank and fall into a notch or between the shanks
or projections on the side of the blank so located in the centre as to allow the
bit to pass through the slot for this purpose will be sufficient. In this case, the bolt
blank will in some degree subserve the purpose of a guide part. The shanks
or these are here to catch back or lateral of pleasure instead of hanging the
shanks to the case as in the common locks so as to bring the blank to the bolt
so that they may move back and forth with it, instead of having a projection
on the blank to face out corresponding notches on the bolt to hold the bolt
and rotate them, as in, where there is no slot in the common locks, the
shanks notched in the lower edges of the tumblers which perform the office to
catching on the edge of the transverse partition in the case. The partitions
may extend nearly from bottom to top of the case and have notched top
so as to guide the sides of the tumblers and the bolt-blank in their movement
in which case the tumblers will catch on the sides of these partitions or the
partitions may extend over one third or one half the way up so that movement
may be guides in various oblique positions. There may also be notched in
the other edge of the tumblers to catch on the other side of the vertical in the
partitions and prevent the bolt from moving. These tumblers are made
so high by false keys or otherwise so that the partitions do not extend above
the tumblers these notches may catch on a cross bar extending across the
case from side to side above the tumblers. The relative position of the tum-
blers and blank of the bolt may be varied to suit variety to the locks or
this variety may be still further multiplied by having notches of different
depth in the sides of the key for the tumblers to fall into. By varying the relative
position of the tumblers and blank in the different arrangements, the
arrangement to prevent false keys will probably afford a sufficient variety for
all ordinary purposes, especially at the least practicable expense. When
therefore we prefer to all others is to place the tumblers of one only one of them
of the two in the centre so that it may fall into the same notch of the key. In
the latter is introduced an auxiliary or the other of the two, thus taking one

place the key in this degree, subduing the pressure of the middle or bridge bar to the lock. In this case a great variety will be produced according to the depth of the lock & the thickness of the bridge bar, not exceeding the thickness of the bridge bar, by varying the depth of one or the other or both of the notches in the key, with which they respectively fall.

The Turner's Spring may act in several manners, according to the proportion of the bridge bar to the thickness of the lock. It may be secured in various ways, either to the case bolt or turner. When the turners are attached to the bolt we prefer to attach them, so as to be able by ribbing them to an arm projecting from one side of it about one inch or less. Encountering the case above mentioned it receives a piece enough to cover its upper edge & interior side. We do it purposely, because we consider the lock complete without it. It adds nothing either to the obvious security, utility or durability of the lock and may therefore be dispensed with. An economy is gained at, & however to use article & Furthermore it may be turned more safely with a cap than may be added to, turned down, & sharp and good notched would be to press the interior of the notched part of the upper edge of the lock in a thin metal, having its end turned down to cover the end of the case. The key, however, not being notched, will in any respect from the key hole before it will except the form of the notched already described which must be made before to the previous case construction arrangement and position of the interior machinery of the lock. The Catch's Part. This does not necessarily differ from the corresponding part of a common turning lock. The key hole is not turned & dropped in the hole mentioned, differ from those hatches are to use in doing so except from the door by projections backwards & to leave room behind them, so the drop shall the drop being below it either in a first projection backwards from the catch or in one of the bars mentioned, of which it is bound to the door by means of the construction. The drop may be made with the side of this projection or drop which should be sufficient & long as usual in the outside of the escutcheon. The drop should be a distance from the point reaching beyond the edge of the escutcheon either at the top or middle near the bottom by means of which it may be introduced into the key hole. The

the key is introduced. The Mortice lock, the above described & known or is believed to be, new in the following particulars which are deemed important as
 mainly constituting & the compacted & its form & the facility of its construction
 & which severally and collectively & together combined, distinguish the lock
 as claimed in our invention that is the combining a case whose two sides
 are upon the edge of the frame with the blade as herein described of having the
 Mortice lock by attaching thereto the bolt, ^{the} upper edge of the case or box
 a slot board which the bit of the key is turned about it acting the bolt & the
 other edge is the lower edge & bottom & in so constructing the case as to have
 it open or capable of being opened in the purpose of receiving & adjusting the
 interior machinery of the lock on its upper edge & not on either side or bottom
 or edge. & about entering the key hole, that when the key is introduced it lie
 may pass in whole or in part below the bottom of the case & in using the edge
 or bottom of the case in the working the lock by cutting it to correspond to the
 or to part to the form of the key & in combining a bolt moved by the action
 of the key, so a notch is between & marks on the edge of its shank with points
 passing into slots or recesses in the bit of the key & so protecting the tumblers
 or of the working that it may fall into the same notch or keep in the bit of
 the key whether the key be introduced from one side or the other of the door. & the
 combining the notches as herein described of having the tumblers by attack
 ing them to the bolt with the notch as herein described of giving them
 direct security to the lock case by having several tumblers falling into correspond
 ing notch, & also, facility of taking off the bolt of the key & the shank, the
 shank being the key part, & then when the foregoing, eight immu
 nient particulars are all applicable to locks described, & the Mortice lock are
 so therefore claim them all in their application to Mortice locks except where
 with the exception of the first two last, they are equally applicable and in the
 same manner to other locks as to the foregoing described with the exception
 of the first & second to other locks, & not applying to other locks, except our designation
